Primary Examiner—Ian Simmons*Assistant Examiner*—R. Johnson(74) Attorney, Agent, or Firm—Albert Jacobs LLP; Albert L. Jacobs, Jr.; Gerard F. Diebner(57) CLAIM

The ornamental design for a trousers with stitched pocket, as shown and described.

DESCRIPTION

FIG. 1 is a front view of trousers with stitched pocket showing my new design;

FIG. 2 is a front view of the trousers with stitched pocket, turned inside out and showing the stitched pocket design; and, FIG. 3 is a fragmentary front view thereof.

The broken lines in the drawings are for illustrative purposes only and form no part of the claimed design. The broken lines in FIGS. 3 are only used to illustrate purposes to indicate a position of a seam, stitching, or a zipper that could be located at the position indicated by the broken line.
